(57) CLAIM

The ornamental design for an hair band with ribbons, as shown and described.

DESCRIPTION

FIG. 1 is a front elevational view of a hair band with ribbons showing my new design, the opposite side is a mirror image; and,
FIG. 2 is a view of the hair band with ribbon as seen in the hair.

The broken line showing of the human form in FIG. 2 is for illustrative purposes only and forms no part of the claimed design.
